UNITED STATES PATENT OFFICE.

HARRY VISSERING, OF CHICAGO, ILLINOIS, ASSIGNOR TO HARRY VISSERING AND COMPANY, OF CHICAGO, ILLINOIS, A CORPORATION OF ILLINOIS.

SAND-PIPE FOR SANDER DEVICES.

1,018,143.

Specification of Letters Patent. Patented Feb. 20, 1912.

Application filed July 1, 1910. Serial No. 569,956.

To all whom it may concern:

Be it known that I, HARRY VISSERING, a citizen of the United States, and a resident of Chicago, in the county of Cook and State 5 of Illinois, have invented certain new and useful Improvements in Sand-Pipes for Sander Devices, of which the following is a specification.

My present invention relates to sanding 10 apparatus and especially to sander devices such as are used for the delivery of sand adjacent the points of contact between locomotive driver wheels and the rails upon which they run.

It contemplates particularly the provision of an improved compensatory connection between the sand delivery pipe connected to the sand box carried on the boiler and a sand ejector pipe carried upon one 20 of the wheel trucks, such construction being required for the successful operation of sander devices used on articulated locomotives, such as what are known as the Mallet type, wherein the trucks are movable relatively to the boiler.

In certain of the sand delivery devices in use at this day, known to me, use is made of various forms of so-called flexible pipes, which flexible elements are objectionable in 30 this, that they do not adequately compensate for the movement of the truck relatively to the sand box, and furthermore, quickly wear out in service, thereby increasing the cost of maintenance of the sander in operative 35 condition. Some effort has been made to overcome these objections by carrying the sand box on the truck, but this construction is undesirable because the sand cannot be so well protected from dampness and because in locomotive practice the drying of 40 the sand is not thereby so efficiently accomplished as when the sand is carried in a dome on the boiler.

The principal objects of my present invention are to provide a compensatory connection between the sand delivery and sand ejector pipes, and a connection between such pipes which will compensate not only for the lateral movement between the trucks 50 and boiler, but also allow the requisite lengthening of such piping;—the provision of an improved form of reciprocating flexible connection and one which offers no angular or other resistance to the free passage 55 of the sand; the provision of means for pre-

venting entrance of moisture into the connecting device or pipes attached thereto, with consequent packing of sand in the pipe and partial retardation or entire prevention of ejection of the sand, together 60 with such other objects as may hereinafter appear.

In overcoming the stated objections and attaining not only the above mentioned objects, but also certain additional advantages 65 to be below disclosed, I have provided a construction, one embodiment of which is illustrated in the accompanying drawings, wherein—

Figure 1 is a diagrammatical representation 70 of a Mallet type locomotive having my improved sand pipe for sander devices applied thereto. Fig. 2 is a longitudinal view, partly in section, of the connection between the sand delivery pipe and sand ejector pipe 75 illustrated diagrammatically in Fig. 1.

Referring now more particularly to Fig. 1 of the drawings, it will be observed that I have here shown, for the purpose of illustration of the use of my improved sander 80 device, a locomotive wherein the boiler 10 is pivotally mounted at 11 upon a truck 12. For the purpose of delivery of sand carried in the sand box 14 adjacent the points 15—15 of the contact between the wheels 13 and the rail 16, I provide sand delivery pipes 17—17 leading to sand trap 18 adjacent the box 14, and mount on the truck 12, as indicated at 20—20, the ejector pipes 21—21 connecting the pipes 17 and 21 by 90 compensating universally movable connections 22—22, now to be more fully described in connection with Fig. 2.

On inspection of Fig. 2 of the drawings, it will be observed that the pipes 17 and 21 95 carry respectively universal joints 23—23A, which are structurally in all substantial respects alike, such joint comprising essentially coöoperating ball and socket members 24 and 25, the ball being retained in the 100 socket by means of a clamping ring 26 which is adjusted in position by means of screw bolts 27—27 having lock nuts 28—28 which are held in position by means of a wire 29 passing therethrough. Within the 105 member 24, is arranged a seat 30 for a spring 31, the opposite end of which spring rests upon a flange 32 formed upon an extension 33 of the socket member, encircling which extension are the spring 31 and seat 110

30. The ball member 24 is provided with an extension 33 internally threaded at 34 to receive the pipe 35, which construction makes a smooth connection between the extension 5 33 and said pipe and is adapted to deliver the sand freely to a pipe 36 threaded into a similar extension 37 on the joint 23^a.

For the purpose of preventing the entrance of any moisture, such as rain or water of condensation which might be deposited upon the outer surface of the pipe 35, thereby dampening the sand and more or less seriously interfering with the operation of the device even to the extent of rendering it inoperative, the extension 33 is likewise threaded externally to carry an internally threaded coupling 38 within which is mounted pipe 39 which acts as a guard to prevent the entry of water or the 15 deposit of moisture upon the pipes 35 and 36. It also serves to maintain such pipes in alignment and obviate any tendency to buckling, which would prevent free reciprocation of the pipes as the truck turns relatively to the boiler while the locomotive is rounding a curve.

From the foregoing description, it will be apparent that by use of my improved sand delivery pipe connection a smooth delivery pipe is provided which not only lacks angularities hindering the ejection of sand, but also compensation is made not only for the lateral strains upon the piping as well as for the increase in the length of such 35 piping required as the truck moves relatively to the boiler.

Having thus described my invention and illustrated its use, what I claim is new and desire to secure by Letters Patent is the 40 following:

1. In an apparatus of the character described, in combination, a sand delivery pipe provided with a universal joint member, a sand ejector pipe provided with a 45 universal joint member and a reciprocating connection between said pipes, provided at each end with universal joint members respectively co-acting with said first mentioned universal joint members.

2. In an apparatus of the character described, in combination; a sand delivery pipe provided with a universal joint member, a sand ejector pipe provided with a 55 universal joint member and an extensible connection between said pipes, provided at each end with universal joint members respectively co-acting with said first mentioned universal joint members.

3. In an apparatus of the character described, in combination, a sand delivery pipe provided with a universal joint member, a sand ejector pipe provided with a 60 universal joint member and a flexible and reciprocating connection between said pipes, provided at each end with universal joint

members respectively co-acting with said first mentioned universal joint members.

4. In a locomotive having a truck and a boiler pivotally mounted upon said truck in combination, a sand ejector member carried by the truck and having a universal joint member, a sand delivery member carried by the boiler and having a universal joint member,—and an extensible connection between said delivery and ejector members, provided at each end with universal joint members co-acting with said first mentioned universal joint members. 70

5. In a locomotive having a truck and a boiler pivotally mounted upon said truck in combination, a sand ejector member carried by the truck and having a universal joint member, a sand delivery member carried by the boiler and having a universal joint member,—and a reciprocating connection between said delivery and ejector members, provided at each end with universal joint members co-acting with said first mentioned universal joint members. 80

6. In a locomotive having a truck and a boiler pivotally mounted upon said truck in combination, a sand ejector member carried by the truck and having a universal joint member, a sand delivery member carried by the boiler and having a universal joint member,—and a flexible connection between said delivery and ejector members, provided at each end with universal joint members co-acting with said first mentioned universal joint members. 90

7. In a locomotive having a truck and a boiler pivotally mounted upon said truck in combination, a sand ejector member carried by the truck, a sand delivery member carried by the boiler, and a universal joint between said delivery and ejector members, one of said members being provided with a guard to prevent the entrance of moisture therewithin. 105

8. In a locomotive having a truck and a boiler pivotally mounted upon said truck, a sand ejector member carried by the truck, a sand delivery member carried by the boiler, said members carrying reciprocating pipe connections and one of said members being 110 provided with a guard to prevent the entrance of moisture therewithin. 115

9. In a locomotive having a truck and a boiler pivotally mounted upon said truck, in combination, a sand ejector member carried by the truck, a sand delivery member carried by the boiler, and a universal joint between said delivery and ejector members, said members carrying reciprocating pipe connections and one of said members being 120 provided with a guard to prevent the entrance of moisture therewithin.

10. In a locomotive having a truck and a boiler pivotally mounted upon said truck, in combination, a sand ejector member car- 125

ried by the truck, a sand delivery member carried by the boiler, a reciprocating member between said first mentioned members having a universal joint at each end connecting said reciprocating member to said first mentioned members and a guard to prevent the entrance of moisture within said reciprocating member.

In testimony whereof I have hereunto signed my name in the presence of the two 10 subscribed witnesses.

HARRY VISSERING.
